Elmer J. Key of Lowell, Mass.

DES. 1976

Assignor to

The Lowell Manufacturing Company of the same place.

Letters Patent No 1976 Dated July 14th 1864.

Design for a Carpet Pattern.

The schedule referred to in these Letters Patent and making part of the same.

Scale upon it may concern.

Be it known that Elmer J. Key of Lowell, in the County of Middlesex and State of Massachusetts, have originated and designed a new Pattern for carpets or other fabrics, of which the following is a full, clear and exact description, reference being had to the accompanying drawings making part of this specification.

In corner A. is one fourth of a large set figure resting on the ground 1, which is surrounded by the scalloped band 2 and frame 3.

In corner B. is one fourth of a plain block resting on the checkered figure 4.

The groups 5, 6, 7 form one fourth of a large wreath which surrounds the figures of corner B.

At the side is one half of a plain block supporting a small set figure and resting on the figure 8, which has an indented edge.

Running parallel with the sides of figure 8 are the broad bands 9 and 10, which intersect at right angles in the centre of the drawings.

The remainder of design consists of a ground work of small crosses.

The colors employed for the different portions of the design may be varied to suit the taste and wish of the manufacturer.

Claim.

What I claim as my invention and desire to secure by Letters Patent, the design or pattern for carpets or other fabrics, herein set forth.
